(57) **CLAIM**

I claim the ornamental design for a ring, as shown and described.

DESCRIPTION

FIG. 1 is a top front isometric view of a first embodiment of a ring showing my new design;

FIG. 2 is a bottom front isometric view thereof;

FIG. 3 is a front elevational view thereof, the rear elevational view being identical thereto;

FIG. 4 is a right side elevational view thereof, the left side elevational view being a mirror image thereto;

FIG. 5 is a top plan view thereof;

FIG. 6 is a bottom plan view thereof;

FIG. 7 is a top front isometric view of a second embodiment of a ring showing my new design;

FIG. 8 is a bottom front isometric view thereof;

FIG. 9 is a front elevational view thereof, the rear elevational view being identical thereto;

FIG. 10 is a right side elevational view thereof, the left side elevational view being a mirror image thereto;

FIG. 11 is a top plan view thereof; and,

FIG. 12 is a bottom plan view thereof.

The broken lines shown in FIGS. 1-6 represent recesses and form no part of the claimed design. The broken lines shown in FIGS. 7-12 represent recesses, through holes and decorative stones and form no part of the claimed design.
